[57] CLAIM

The ornamental design for a magnetic recording disk cartridge, as shown and described.

DESCRIPTION

FIG. 1 is a top, front, right side perspective view of a magnetic recording disk cartridge showing our new design;

FIG. 2 is a front elevational view thereof;

FIG. 3 is a back elevational view thereof;

FIG. 4 is a left side elevational view thereof, the right side elevational view being a mirror image;

FIG. 5 is a top plan view thereof;

FIG. 6 is a bottom plan view thereof.

UNITED STATES PATENT AND TRADEMARK OFFICE
CERTIFICATE OF CORRECTION

PATENT NO. : Des. 307,893

DATED : May 15, 1990

INVENTOR(S) : Arthur K. Kato, et. al.

It is certified that error appears in the above-identified patent and that said Letters Patent is hereby corrected as shown below:

On Title page, Assignee should read as follows:

Item [73] Assignee: Minnesota Mining and Manufacturing Company,
St. Paul, Minnesota and Sony Corporation, Tokyo, Japan

Signed and Sealed this

Twenty-ninth Day of December, 1992

Attest:

DOUGLAS B. COMER

Attesting Officer

Acting Commissioner of Patents and Trademarks
